(57) **CLAIM**

The ornamental design for a light projection device, as shown and described.

DESCRIPTION

FIG. 1 is a front, top, left perspective view of a light projection device showing my new design therefor;

FIG. 2 is a rear, top, right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, top, left perspective view of a second embodiment of a light projection device showing my new design therefor;

FIG. 10 is a rear, top, right perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

Surfaces considered part of the claimed design are provided with surface shading. Where a broken line forms the boundary of a claimed surface, that broken line is intended to represent an unclaimed boundary, which forms no part of the claimed design. All remaining broken lines are intended to represent portions of the light which form no part of the claimed design.
